DORINE FOR LOOSE POWDER

Filed Dec. 14, 1925

INVENTOR
James L. Younghusband

By Charles A. Mills

UNITED STATES PATENT OFFICE.

JAMES LESLIE YOUNGHUSBAND, OF CHICAGO, ILLINOIS.

DORINE FOR LOOSE POWDER.

Application filed December 14, 1925. Serial No. 75,182.

This invention relates to powder containers and more particularly to means for retaining loose powder in dorines, vanity boxes and the like.

5 The cake form of face powder has not proven entirely satisfactory for the reason that the binders generally used to hold the powder together have deleterious effects upon the skin. Furthermore, the powder cakes are very fragile and break easily, causing considerable annoyance to the user. On the other hand, it is difficult in the ordinary vanity case to prevent a loose powder contained therein from spilling.

10 15 It is therefore an object of this invention to provide improved means for retaining loose powder in a container to prevent spilling the same.

It is a further object of this invention to 20 provide a container for loose face powder wherein the powder puff, or applicator, is adapted to resiliently fit the inside of the container to prevent the leakage of the loose powder past the puff.

25 Other and further important objects of this invention will be apparent from the disclosures in the specification and the accompanying drawings.

The invention (in a preferred form) is illustrated in the drawings and hereinafter more fully described.

On the drawings:

Figure 1 is an elevational view of a powder compact or dorine embodying the principles of my invention.

Figure 2 is an enlarged longitudinal section showing parts in elevation.

Figure 3 is a reduced longitudinal section of the applicator.

40 Figure 4 is an elevational view of a modified form of my device, showing parts broken away and in section.

Figure 5 is a sectional view taken on line V—V of Figure 4, with the applicator in place in the container.

As shown on the drawings:

The reference numeral 1 indicates a powder compact or dorine comprising a receptacle 2 and a cover 3 therefor, preferably formed of metal and cylindrical in shape.

The cover 3 may be either frictionally retained by the receptacle 2 or it may be hinged thereto. The receptacle 2 contains a loose face powder 4 in place of the usual powder cake. An applicator 5 is adapted to fit with- 55 in said receptacle 2 above said powder 4. Said applicator 5 comprises a filler 6 of suitable fluffy material enclosed between an upper surface 7 of plush material, and a lower surface 8 of felt or other suitable material 60 secured to said upper surface as at 9.

Thus far the construction of the applicator is of the usual type but such construction is not suited for use with loose powder for the reason that the applicator so constructed 65 permits the powder to leak out around its edges and spill from the compact. I have found that by providing the lower surface 8 with an inner lining 10, formed of some resilient, flexible material such as rubber, the 70 edges of the applicator are held in an extended position and will, when placed in the receptacle 2, resiliently engage the wall of said receptacle to prevent leakage of powder past the edges of the applicator. The re- 75 sili ent lining 10 causes the lower surface 8 of the applicator naturally to assume a convex position as shown in Figure 3 but when placed in the receptacle 2 the pressure of the applicator against the loose powder beneath causes the surface 8 of the applicator to straighten out whereby its edges exert a 80 resilient pressure against the wall of said receptacle.

In Figures 4 and 5 there is shown a slight 85 modification of my invention wherein a wire spring 11 is substituted in place of the resilient lining 10. Said spring 11 is provided with an expansion sleeve or loop 12 to allow said spring to expand and contract. The 90 spring 11 is positioned inside the circumferential edge of the lower face 13 of the applicator whereby it tends to hold the applicator in extended position. The lower face 13 is here shown as formed of plush material 95 but it is obvious that any suitable material may be used. The spring 11 serves the same purpose as the resilient lining 10, to hold the edges of the applicator against the wall of the compact to prevent the spilling of the 100

loose powder. The spring 11 is of such light construction as to be easily flexed to allow the applicator to conform with any portion of the face that is being powdered.

5 I am aware that numerous details of construction may be varied through a wide range without departing from the principles of this invention, and I therefore do not purpose limiting the patent granted hereon,

otherwise than necessitated by the prior art. 10

I claim as my invention:

A powder applicator having a lining of resilient flexible material adjacent one face thereof adapted to hold said applicator in 15 extended lateral position.

In testimony whereof I have hereunto subscribed my name.

JAMES LESLIE YOUNGHUSBAND.
